[57] CLAIM

The ornamental design for a video cassette package, as shown and described.

DESCRIPTION

FIG. 1 is a perspective view of a closed video cassette package showing our new design;

FIG. 2 is a perspective view thereof, shown in an opened position;

FIG. 3 is a perspective view of an alternate embodiment of FIG. 1, shown in an opened position, the remaining views of the second embodiment are identical to the first embodiment;

FIG. 4 is a front elevational view of FIG. 2, the rear view being a mirror image; and,

FIG. 5 is a left side elevational view thereof.

The undisclosed rearview forms no part of the claim design. The broken line showing of the cassette tape on FIGS. 4 and 5 is for illustrative purposes only and forms no part of the claimed design.
